UNITED STATES PATENT OFFICE.

FRANZ BERGER-HAHNEL, OF ULLGERSDORF, NEAR BODENBACH, AUSTRIA-HUNGARY.

KEYHOLE-GUARD.

1,105,544.

Specification of Letters Patent.

Patented July 28, 1914.

Application filed July 16, 1913. Serial No. 779,388.

To all whom it may concern:

Be it known that I, FRANZ BERGER-HAHNEL, a subject of the Emperor of Austria-Hungary, and resident of Ullgersdorf, 5 near Bodenbach, Böhmen, Austria-Hungary, have invented certain new and useful Improvements in Keyhole-Guards, of which the following is a specification.

This invention relates to an improved key-10 hole guard, which essentially comprises a shell designed to be inserted in the keyhole of a lock and fitted with pivotal wings, which by means of a key can be made to transversely project from the shell after 15 insertion of the latter, so that the same cannot be removed but with the aid of said key.

The accompanying drawing shows the improved guard.

Figures 1 and 2 are respectively a longitudinal central section and a cross section 20 through the same, with the wings in their inoperative position, while Figs. 3 and 4 are similar sections to the former, with the wings in their operative position. Fig. 5 shows, in a perspective view, how the guard 25 is inserted in a keyhole, with the key belonging thereto.

The improved guard comprises an open-ended shell *a*, which is designed to be inserted in the keyhole of a lock. In said shell, two fixed bridges *b* are located for the reception of a revoluble spindle *c*. Between the two bridges the spindle is provided with screw-threads with a nut *d* thereon. The 35 latter carries pivotal wings *e*, which, when the nut assumes one of its end positions, project with their ends somewhat through slots *f* in the walls of the shell in such a way that said ends are prevented from entering 40 the interior of the shell. The ends of the spindle *c* projecting beyond the bridges are provided with square portions for the reception of a key *h* (Fig. 5) inserted through either end of the shell. The shell carries a

laterally projecting outer rib *g* for preventing it from turning after its insertion in the keyhole of the lock.

The operation of the improved guard is as follows:—Before insertion of the shell in a keyhole, the nut *d* is screwed into that of its 50 end positions, in which the wings *e* do not transversely project therefrom. The shell is then so inserted in the keyhole that the projection *g* thereon lies within the slot of the keyhole. By means of a key *h*, the spindle 55 is then turned, whereby the nut is removed thereon in such a way that the wings, which with their front ends strike against the ends of the slots *f*, project transversely from the shell. After removal of the key, the shell 60 cannot be removed from the keyhole but by again inserting the key *h* therein, the disengagement of the wings being then effected in the same way but vice versa.

What I claim is:

A keyhole guard comprising in combination, an open-ended shell having slots in its walls and a laterally projecting outer rib, bridges in said shell, a screw-spindle revolvably mounted in said bridges, a nut on that 70 part of the spindle lying between said bridges, key-operated square portions on the ends of said spindle projecting beyond said bridges, and pivotal wings so arranged on said nut that they are disposed within the 75 shell but prevented from entirely entering the latter upon the nut being screwed into one of its end positions while they project transversely therefrom upon the nut being screwed in other directions, substantially as 80 described and shown.

In testimony whereof I have hereunto set my hand in the presence of two subscribing witnesses.

FRANZ BERGER-HAHNEL.
